W. P. ORR.
BROOM PRESS.
APPLICATION FILED JUNE 18, 1921.

1,418,018.

Patented May 30, 1922.

Inventor

W.P. Orr:

By Watson E. Coleman
Attorney

UNITED STATES PATENT OFFICE.

WALKER P. ORR, OF DIANA, TENNESSEE.

BROOM PRESS.

1,418,018.

Specification of Letters Patent. Patented May 30, 1922.

Application filed June 13, 1921. Serial No. 478,640.

To all whom it may concern:

Be it known that I, WALKER P. ORR, a citizen of the United States, residing at Diana, in the county of Giles and State of Tennessee, have invented certain new and useful Improvements in Broom Presses, of which the following is a specification, reference being had to the accompanying drawings.

10 This invention relates to broom presses for use in manufacturing brooms, and has for its object to provide a press capable of firmly holding the broom straw in the desired form for twining.

15 It is another object of the invention to provide a device of this character arranged to receive any quantity of broom straw, and wherein means are provided for firmly holding the straw within the press.

20 It is also an object of the invention to provide a device of this character wherein the means for holding the broom straw or material within the press may be adjusted to accommodate the desired quantity of material.

25 With these and other objects in view the invention consists in the improved construction and arrangement of parts to be herein-after more particularly described, fully 30 claimed and illustrated in the accompanying drawings, in which:—

Figure 1 is a plan view of a broom press constructed in accordance with an embodiment of the invention, a portion of the device being shown in section,

Figure 2 is a side elevation of the structure shown in Figure 1,

Figure 3 is an end view of the structure shown in Figure 1, and

40 Figure 4 is a perspective view of the connecting means of the flexible member.

Referring to the drawings, 5 designates a body member or press having a relatively wide end portion 6, said end portion having a recess 7 which extends inwardly a considerable distance and terminates adjacent the edges of said end. This recess is adapted to receive the broom straw or material to be held in the manufacture of the broom. The 45 longitudinal edge 8 of the press inclines inwardly and then outwardly to provide an extension 9, while projecting from the longitudinal edge 10 is an extension 11, the end 12 of the body member being rounded, the

purpose of which will be hereinafter described.

The arms 13 formed by the recess 7 on the end 6 of the press are each provided with channels 14 adapted to receive a flexible clamping member 15, preferably a strap. 60 The end 16 of the clamping member is secured to the edge 8 of the press and is adapted to be disposed in the channels 14 of the arms 13 to prevent the member from moving laterally of the end 6. The end 17 of 65 the clamping member is provided with a loop 18 adapted to receive a hook 19 for holding the strap in various adjusted positions.

Projecting from the edge 10 of the press adjacent the end 6 is a pair of ears 20, said ears being either attached to the body member or formed integral therewith. A lever 21 is pivoted at its end 22 between the ears 20 and is intended to be disposed in parallel relation to the edge 10 of the press, the end 70 23 of the lever being arranged to substantially register with the extension 11. The outer face of the lever is provided with a longitudinally extending recess 24, over which a plate 25 is disposed, said plate having 75 a series of openings 26. One end of the plate is formed into a bearing 27 adapted to receive a loop member 28. The loop member is relatively large so as to permit the same to extend over the extension 11 and engage 80 the rounded end 12 of the press, whereby the lever 21 is held substantially parallel to the edge 10 of the press.

In the use of the device, the broom straw or material is placed in the recess 7 of the press and the lever 21 swung upwardly toward the end 6 so as to permit the hook 19 to be disposed in the desired opening of the plate 25, according to the quantity of straw disposed in the recess. The lever 21 90 is then swung downwardly toward the edge 10, whereby the straw is properly compressed within the recess 7 through the co-operation of the flexible clamping member or strap 15. The loop 28 is then swung over 100 the extension 11 and into engagement with the end 12. The broom material is thereby firmly clamped into position and is ready for twining, it being impossible for any of the broom straw to leave the bundle while 105 held within the press.

From the foregoing it will be readily seen that this invention provides a novel form of

broom press which is simple in construction and may be operated by anyone. It is of course obvious that I do not desire to limit myself to the precise arrangement of the 5 press, as various changes may be made to permit the manufacture of brooms of various styles, without departing from the spirit of my invention.

What is claimed is:—

- 10 1. A broom press embodying a body member having a recess for the reception of broom material, means carried by the body member for holding various quantities of broom material within the recess, said means comprising a flexible member secured at one end to the press and adapted to extend over a recess, an adjusting member movably connected to the body member, the opposite end of said flexible member being detachably connected to the adjusting member.
- 15 2. A broom press embodying a body member having a recess for the reception of broom material, and means carried by the body member for holding various quantities of broom material within the recess, said means comprising a flexible member secured at one end to the body member and adapted to extend over said recess, the opposite end of said member being provided with a hook, 20 a lever pivoted to the body member, said lever being provided with means adapted to be engaged by the hook to permit adjustment of the flexible member according to the quantity of material within the recess, and 25 means carried by the end of the lever to prevent movement of the lever with respect to the body member.
- 30 3. A broom press embodying a body member having a recess for the reception of

broom material, and means carried by the 40 body member for holding various quantities of broom material within the recess, said means comprising a flexible member secured at one end to the body member and adapted to extend over the recess, the opposite end 45 of said member being provided with a hook, and a lever pivoted at one end to the body member and arranged to move toward the recess, a plate carried by the lever, said plate having a series of openings adapted to receive a hook to hold the flexible member in various adjusted positions, and a loop carried by the end of the plate adjacent the free end of the lever, said loop being arranged to extend over the end of the body member to hold the lever substantially in parallel relation to the press.

4. A broom press embodying a body member having one end thereof bifurcated to provide a recess for the reception of broom 60 material, a flexible member secured at one end to one side of the body member and extending over the ends of the arms of the bifurcation, the opposite end of said member being provided with a hook, an adjusting lever pivoted at one end adjacent one of the arms of the bifurcation, a keeper carried by said lever, for the reception of the hook of the flexible member, the opposite 65 end of said lever being provided with a fastening member adapted to embrace the opposite end portion of the body member to hold the lever in engagement with said body member.

In testimony whereof I hereunto affix my 70 signature.

WALKER P. ORR.
